US00D972946S

(12) **United States Design Patent** (10) **Patent No.:** **US D972,946 S**
(45) **Date of Patent:** **** Dec. 20, 2022**

(54) **BUILDING CONTROLLER**

(71) Applicant: **Honeywell International Inc.**, Morris Plains, NJ (US)

(72) Inventors: **Zhiguo Di**, Morris Plains, NJ (US); **Yidan Zhao**, Shanghai (CN); **Peilin Li**, Shanghai (CN)

(73) Assignee: **HONEYWELL INTERNATIONAL INC.**, Charlotte, NC (US)

(**) Term: **15 Years**

(21) Appl. No.: **29/716,912**

(22) Filed: **Dec. 12, 2019**

(51) LOC (13) Cl. **10-04**

(52) U.S. Cl.

USPC **D10/50**; D10/60; D13/168

(58) **Field of Classification Search**

USPC D13/162, 168, 162.1, 177; D10/49, 50,

D10/60; D14/125, 240, 242, 358

CPC F24F 11/30; F24F 11/56; G05D 23/1905;

G08C 17/02; G05B 15/00

See application file for complete search history.

(57) **CLAIM**

The ornamental design for a building controller, as shown and described.

DESCRIPTION

FIG. 1 is a perspective view of a building controller; FIG. 2 is a front side view of the building controller of FIG. 1;

FIG. 3 is a left side view of the building controller of FIG. 1;

FIG. 4 is a right side view of the building controller of FIG. 1;

FIG. 5 is a top side view of the building controller of FIG. 1; and,

FIG. 6 is a bottom side view of the building controller of FIG. 1.

The portions illustrated in broken lines on the figures are for illustrative purposes only and form no part of the claimed design.

1 Claim, 6 Drawing Sheets
